CONTAINER FOR SIPPABLE LIQUIDS
OR THE LIKE

Mary E. Cammack, 350 E. Rustic Road,
Santa Monica, Calif.

Filed Apr. 2, 1964, Ser. No. 79,322

Term of patent 14 years

(Cl. D58—9)

Fig. 1

Fig. 2

Fig. 3

The side and bottom not shown are substantially the same as the side and top shown.

I claim:

The ornamental design for a container for sippable liquids or the like, substantially as shown and described.
